UNITED STATES PATENT OFFICE

ALFRED C. ALLEN, OF WASHINGTON, DISTRICT OF COLUMBIA
FOLDABLE NOTE PAD HOLDER FOR STENOTYPE OPERATORS

Application filed September 30, 1930. Serial No. 485,524.

The object of my invention is to provide a convenient foldable holder for the use of stenotype operators for holding the continuous paper pads on which stenotype notes are made and to permit of readily shifting this pad to bring a new section of the notes into view as transcription on the typewriter progresses.

It is also an object of my invention to provide such a holder which permits of convenient access to the note pad to apply it and to remove it and also which permits of making notations on the portion or section of the stenotype notes presented to view for transcription and which will also permit the paper to fall into a smooth position in a separate compartment as the notes are being transcribed.

It is also an object of my invention to provide a device which can be readily folded into a sufficiently compact flat package to permit of its being readily inserted in an ordinary manuscript case.

It is also an especial object of my invention to provide a device of this character which in addition to operating efficiently can also be manufactured at relatively small cost.

I attain these and other objects of my invention by the device illustrated in the accompanying drawings, in which,—

Figure 1 is a perspective view of my invention in use;

Fig. 2 is a perspective view of my invention in its completely folded position for carrying in a manuscript case or the like;

Fig. 3 is a perspective view of the holder with the side 34 removed;

Fig. 4 is a longitudinal vertical section through the invention;

Fig. 5 is a side elevation of the invention;

Fig. 6 is a vertical section on line 6—6 of Fig. 5;

Fig. 7 is a section on line 7—7 of Fig. 5;

Fig. 8 is a perspective view of the invention with the flaps 21 and 31 in their folded position;

Fig. 9 is a diagrammatic view of the invention in partly folded position the numbered arrows indicating the order of the folding of the various members of the holder; and

Fig. 10 is a similar diagrammatic view of the final stage of folding the holder.

Like numerals designate like parts in each of the several views.

Referring to the accompanying drawings, I provide a base member 1, having opposite longitudinal folded over edge strips 2 to engage the strip 4 on which the stenotype note pad C is placed. The strip 4 has an upturned rear end or flange 5 and an upturned front edge or flange 6, as shown in Figs. 4 and 8. I also provide a raised portion 7 to which is affixed the spring 12 attached to one end of the roller 10, which roller is positioned between the upturned end 6 and the raised portion 9, which functions as a stop for the front end of the stenotype pad. I provide roller 10 with an axle 11, the end of which projects to rest on the small raised member or platform at the free end of the roller and which is mounted at latch 13, pivoted at 14 and provided with a small knob 15 at its free end.

I provide a vertical side member 16, hingedly connected with the base 1 by the hinges 3. The side member 16 has a slanting front edge, as shown in Fig. 1, and is provided with the tongue 19 adapted to engage in the slot 32 of front strip 31. Side wall 16 is provided with hinged upper end extension 21 connected with member 16 by suitable hinges 20, as shown in Fig. 8. I also provide a vertical rear wall 23 hingedly connected to side wall 16 by suitable hinges 18. I also provide a horizontal strip 27 for holding the transcribed stenotype notes. Strip 27 is hingedly connected to side wall 16 by hinges 17, as shown in Figs. 3 and 8; and is also detachably fastened to rear wall 23 by a tongue 24 which is insertable through a suitable slot 29 in the rear wall 23. The rear wall 23 is provided with a suitable latch tongue 25 adapted to releasably engage a latch or projection 26 on member 1, as shown in Fig. 5.

I provide a hinged strip 31 mounted by hinges 30 on the front end of horizontal strip 27 and releasably secured in its normal position, as shown in Fig. 1, by a tongue 19, side wall 16 which engages in the lower slot 32 of member 21, and a tongue 22 on side wall extension 21 which engages in the upper slot 10.

22, as shown in Figs. 1 and 8. The front member 31 is provided with a slot 33 in its upper portion, the slot being of slightly greater width than the strip of stenotype note paper, to permit the strip of note paper to move across same and to be guided by the adjacent portions of the front member 31, as shown in Fig. 1. The horizontal strip 27 is provided with a recessed portion 28 to permit the operator to grasp the portion A of the stenotype pad to remove same when desired.

Referring to Figs. 1 and 2, I provide a removable side plate member 34 having a bottom flange 35 to seat under member 1 and a rear vertical flange 36 to engage around the rear wall 23. This side wall is an optional and also a removable member and may be used as a cover member in packing the device.

The operation of the invention will be understood by reference to Figs. 1 and 5 of the drawings. The stenotype note pad which is a continuous strip of paper folded back and forth is placed in the lower compartment on the slideable strip 4 and as first placed in the machine all the paper is on the portion of the pad designated "C". Roller 10 is brought down from its normal vertical to its operative horizontal position and is fastened there by the latch 13, as shown in Fig. 8. The forward end of the note pad C rests against the projection or guide strip 9 and is fed under the roller 10 and then passed upwardly over the slotted portion 33 of the front member 31.

As the operator transcribes his notes on the typewriter later he will grasp the strip of paper B and move it up so that it will gradually fall into a new pad A on the horizontal strip 27, as shown in Fig. 1. As the strip 2 is slidably mounted on the base 1 it is possible to pull out the entire pad to inspect same to determine how many more notes there are to be transcribed, whenever this information is desired. Or the slideable strip 4 may be pulled forward in order that a longer expanse of notes may be in view before the operator if that is desired. A less frequent shifting of the note paper is thereby made possible. The guide strip or projection 9 at one end and the upturned flange at the other, function as guides for the stenotype note pad to hold the pad against any irregular movements.

The device may be readily folded for carrying in a manuscript case and to attain this result, side plate extension 21 is first folded outwardly as indicated by the arrow in Fig. 8 and the front member 31 is folded downwardly on horizontal strip 27 as indicated by the arrow also in Fig. 8. The horizontal strip 27 and front member 31 are then folded upwardly as indicated by the arrow marked "3rd" in Fig. 9. The vertical end member

23 is then pulled inwardly and the base members 1 and 4 are folded upwardly so as to provide a compact flat package over which is placed the detachable side wall 34, as shown in Fig. 2, to function as a cover member.

It is within the contemplation of my invention, if desired, to omit the member 34. It is also within the contemplation of my invention, if desired, to omit the side wall extension 21; also the roller 10 may be mounted in any suitable manner, the preferred form being illustrated in Figs. 3 and 8 of the drawings.

It is also within the contemplation of my invention, if desired, to omit the hinges connecting the various walls and strips and make the connection of these members rigid so as to provide a holder which is not foldable but which is otherwise exactly as illustrated in the accompanying drawings.

What I claim is:

1. In a foldable note pad holder for stenotype operators, the combination of a base, an upright side member hingedly attached to the base, an upright rear member hingedly attached to the side member, a horizontal plate member hingedly connected to the side member for receiving the note paper which has been transcribed, a front member for holding a portion of the note pad to be transcribed, said member being hingedly attached to the horizontal strip, means for supporting said front member in a slanting position, and means for fastening the aforesaid members one to the other in normal position for holding the stenotype note paper.

2. In a foldable note pad holder for stenotype operators, the combination of a base, a strip slidably mounted on the base, said strip having guides at each end thereof for preventing irregular movements of the stenotype note paper on same, a roller mounted on the forward end of the slideable strip to guide the stenotype note paper, an upright side member hingedly attached to the base, a horizontal strip hingedly connected to the side member and spaced substantially above the base to receive the transcribed portion of the stenotype note paper, a front member hingedly connected to said horizontal strip, a side extension hingedly connected to the side member, means for releasably attaching the front member to the side member and side extension, the front member having a cut out portion to guide the strip of stenotype note paper and a rear member hingedly connected to the side member and to which the horizontal strip is detachably connected.

3. In a foldable note pad holder for stenotype operators, the combination of a base, a strip slidably mounted on the base, a roller mounted on the forward end of the slideable strip to guide the stenotype note paper, an upright side member hingedly attached to the base, a horizontal strip hingedly con-

5 nected to the side member and spaced substantially above the base to receive the transcribed portion of the stenotype note paper, a front member hingedly connected to said horizontal strip, a side extension hingedly connected to the side member, means for releasably attaching the front member to the side member and side extension, the front member having a cut out portion 70 to guide the strip of stenotype note paper and a rear member hingedly connected to the side member and to which the horizontal strip is detachably connected.

10 4. In combination with the apparatus defined in claim 1, a roller located at the forward bottom portion of the device to guide the stenotype note paper as it leaves the note pad to be passed across the front member in position for reading the notes.

20 5. In combination with the mechanism defined in claim 1, the bottom edge of the front member being spaced from the base of the device to permit of quick and convenient removal of the note paper, and a roller for 85 guiding the strip of stenotype note paper before it is passed over the front member.

25 6. In a foldable note pad holder for stenotype operators, the combination of a base, the base having longitudinally folded over edge 90 portions, a strip slidably mounted in the base, a roller mounted on the forward end of the strip over which the strip of stenotype note paper is passed, an upright side member having a slantingly disposed front edge, a horizontal strip spaced above the base and hingedly attached to the side member, a front member hingedly attached to the horizontal strip, said front member being adapted to 95 hold a portion of the stenotype note paper in view for transcription, said front member having a slot in its upper portion through which the note paper is passed, a vertical rear wall, and means for detachably fastening the aforesaid members in normal position for 100 holding the stenotype note paper during transcription.

30 7. In combination with the mechanism defined in claim 6, the slidable strip having guide members at each end thereof to retain 105 the pad of stenotype note paper in its proper position on the slidable strip.

35 8. In combination with the apparatus defined in claim 6, the horizontal strip having a lateral cut out portion to permit of readily grasping the transcribed stenotype note paper to remove same.

40 9. In combination with the mechanism defined in claim 6, a second side member having a bottom flange and having an end flange 110 whereby the aforesaid flanges will frictionally engage under the base and end walls respectively of the device when assembled for use.

45 10. In combination with the mechanism defined in claim 1, the front member having

a cut out portion at its upper end and of slightly greater width than the note paper to allow the strip of note paper to pass readily therethrough, whereby the adjacent portions of the front member will function as 75 guide elements for the strip of note paper.

11. In a foldable note pad holder for stenotype operators, the combination of a base, an upright side member attached to the base, an upright rear member attached to one of the adjacent members of the holder, a horizontal plate member attached to the side member for receiving the note paper which has been transcribed, a front member for holding a portion of the note pad to be transcribed, and means for supporting said front member in a slanting position.

12. In a foldable note pad holder for stenotype operators, the combination of a base, a strip slidably mounted on the base, said strip 85 having guides at each end thereof for preventing irregular movements of the stenotype note paper on same, a roller mounted on the forward end of the slidable strip to guide the stenotype note paper, an upright 90 side member attached to the base, a horizontal strip connected to the side member and spaced substantially above the base to receive the transcribed portion of the stenotype note paper, a front member connected to said 95 horizontal strip and to the side member, the front member having a slot cut out of its upper end to guide the strip of stenotype note paper, and a rear member attached to the side member and to the horizontal strip.

13. In a foldable note pad holder for stenotype operators, the combination of a base, a strip slidably mounted on the base and adapted to hold a pad of stenotype note paper, a roller mounted on the forward end of the slidable strip to guide the stenotype note paper, an upright side member attached to the base, a horizontal strip connected to the side member and spaced substantially above the base to receive the transcribed portion 100 of the stenotype note paper, a front member 105 connected to said horizontal strip and to the side member, the front member having a cut out portion to guide the strip of stenotype note paper, and a rear member attached to 110 the side member and connected to the horizontal strip.

14. In combination with the device defined in claim 11, a roller located at the forward bottom portion of the device to guide 115 the stenotype note paper as it leaves the note pad to be passed across the front member in position for reading the notes.

ALFRED C. ALLEN.
